Inventor:
J. U. Johnson.

United States Patent Office.

J. U. JOHNSON, OF SPRINGFIELD, MASSACHUSETTS.

Letters Patent No. 80,549, dated August 4, 1868; antedated July 24, 1868.

IMPROVEMENT IN BOOT-PROTECTOR.

The Schedule referred to in these Letters Patent and making part of the same.

TO ALL WHOM IT MAY CONCERN:

Be it known that I, J. U. JOHNSON, of Springfield, in the county of Hampden, and Commonwealth of Massachusetts, have invented a new and improved Boot-Protector; and I do hereby declare that the following is a full, clear, and exact description thereof, reference being had to the annexed drawings, making a part of this specification, and to the letters of reference marked thereon, in which—

Figure 1 is a perspective view of my said invention.

My invention consists of a metallic guard, of peculiar conformation, and furnished with spurs or projections, and a strap and buckle, for fastening the device to the boot or shoe of the wearer.

It is designed especially for the use of boys while engaged in coasting or sliding upon snow and ice.

It is well known that, in coasting, a sled is usually steered by the right foot, which is projected, and acts like a rudder, while the side of the boot, near the toe, is brought in contact with the surface of the ice and snow, and is soon abraded and worn away.

My invention is designed to prevent this local wear and injury of the leather, by interposing a guard-plate, which completely protects the steering-boot or shoe at the point of contact with the surface of the snow, which is readily fastened to the boot or detached therefrom, and which, also, may be made to serve as an ice-creeper or safeguard from slipping while walking upon ice.

The construction of my invention is as follows:

The device is composed of a metallic portion, which I prefer to construct of malleable iron, and which is cast in one piece, and the straps and buckle for fastening the device to the foot.

The metallic part consists of the bottom, A A, and sides, B and C.

The bottom, which I denominate the sole-plate, is slightly curved from front to back, to conform to that curvature of the sole of a boot from the ball of the foot forward, and may be slotted, as at A', for lightness.

Upon the under side of the sole-plate, I form the spurs d d, &c., to enable the wearer to walk securely upon ice.

Projections b b are also formed upon the upper side of the sole-plate, to enter the sole of the boot, and prevent the protector from slipping forward.

The protector shown is designed for the right foot, but may be adapted to the other, by reversing the sides B and C.

The latter are arranged at right angles to the sole-plate, and are curved to conform to the usual curvature of the corresponding sides of a boot-sole, at the points where the protector is to be applied.

The side C is made longer than B, in the direction of the toe, to entirely protect the steering-side of the boot, and the sole-plate is extended forward at C, to prevent the device from rocking or tipping.

For the same purpose, a sharp spur, d', may be inserted in the forward end of C, if necessary.

Recesses are formed in the sides B and C, to receive the ends of the fastening-straps S S, which are secured therein by rivets s s, and respectively furnished with a buckle, S', and holes for the buckle-tongues.

I have employed a pointed thumb-screw in the side B, which entered the boot-sole, and answered the purpose of the strap and buckle, but prefer the arrangement shown, as being more reliable and convenient, although the spurs d d may be removed, and the bottom of the sole-plate roughened, or even left in a smooth condition, without impairing the utility of my device as a boot-protector, which I claim as novel and useful, apart from its use as an ice-creeper.

Having described my invention, what I claim as new therein, and desire to secure by Letters Patent, is—

As an article of manufacture, the boot-protector, constructed and arranged as described.

J. U. JOHNSON.
